(57) **CLAIM**

The ornamental design for a solar LED wall light, as shown and described.

DESCRIPTION

FIG. 1 is a front view of a solar LED wall light of the present invention.

FIG. 2 is a back view thereof.

FIG. 3 is a left view thereof.

FIG. 4 is a right view thereof.

FIG. 5 is a top view thereof.

FIG. 6 is a bottom view thereof.

FIG. 7 is a perspective view thereof.

FIG. 8 is a perspective view of the solar LED wall light of the present invention, when a back panel with LED lights is swiveled open; and,

FIG. 9 is another perspective view of the solar LED wall light shown in FIG. 8, observed from a different angle.

The broken lines show portions of the solar LED wall light which forms no part of the claimed design.
